(57) **CLAIM**

The ornamental design for an ocular incision guide tool, as shown and described.

DESCRIPTION

FIG. 1 is a top, front, and left side perspective view of a first embodiment of an ocular incision guide tool showing our design;

FIG. 2 is a bottom, rear, and right side perspective view thereof;

FIG. 3 is a left side view thereof;

FIG. 4 is a right side view thereof;

FIG. 5 is a top view thereof;

FIG. 6 is a bottom view thereof;

FIG. 7 is a front view thereof;

FIG. 8 is a rear view thereof; and

FIG. 9 is a close-up view of a portion of the ocular incision guide tool shown in FIG. 2.

FIG. 10 is a top, front, and left side perspective view of a second embodiment of an ocular incision guide tool showing our design;

FIG. 11 is a bottom, rear, and right side perspective view thereof;

FIG. 12 is a left side view thereof;

FIG. 13 is a right side view thereof;

FIG. 14 is a top view thereof;

FIG. 15 is a bottom view thereof;

FIG. 16 is a front view thereof;

FIG. 17 is a rear view thereof; and,

(Continued)

FIG. 18 is a close-up view of a portion of the ocular incision guide tool shown in FIG. 11. The dash-dot broken lines illustrate boundary lines that form no part of the claimed design.
